UNITED STATES PATENT OFFICE.

JOHN EDWARD GLOEKLER, OF PITTSBURGH, PENNSYLVANIA.

SUPPORTING BRACKET FOR PARALLEL RAILS, RODS, AND THE LIKE.

Application filed October 9, 1925. Serial No. 61,522.

Although my improved bracket may be advantageously employed for the support of parallel members in general, I have more particularly designed it for supporting tray-
5 rails in cafeterias.

In cafeterias a plurality of parallel rails extend along the front of the counter or serving table, and the patrons rest their trays on said rails and slide them along the
10 latter as they select and receive the articles of food desired.

In the accompanying drawings, wherein I have illustrated the best embodiment of the principles of my invention now known to
15 me, showing the same applied to the tray-
rails of a cafeteria, Fig. 1 is a perspective view showing the bracket as used; Fig. 2 is a side elevation of the bracket; Fig. 3 is a plan view of the same; Fig. 4 is a section
20 thereof taken along the line IV—IV in Fig. 2, and Fig. 5 is a perspective of one of the clamping plates which I employ to secure the rails to the bracket.

Referring to the drawings A represents
25 the counter or table upon which the food is displayed and from which it is served, and B represents one of the brackets which at properly spaced intervals support the tray-
rails C.

30 The brackets are preferably of cast metal and are provided at their butts with the flat plates 1. Said plates may be cast integral with the brackets, but I prefer to attach them to the brackets as by the screws
35 2. The plates 1 are provided with screw holes for the screws 3 by which they are attached to the front of the counter A.

The top surface of the bracket is preferably horizontal and provided at or near its
40 outer end with an upwardly extending lug 4 having its inner face arcuate or concaved to fit against the outside rail C. Near its inner end the top surface of said bracket is provided with a second lug 5 having its
45 outer face arcuate or concaved to similarly fit against the inside rail C.

D represents a pair of clamp-plates having their ends enlarged and provided with arcuate or concaved surfaces adapted to fit
50 the rails, so that when the rails and the clamp-plates are in place, as shown in the drawings, the arcuate surfaces of the two lugs 4 and 5 and the arcuate ends of the

clamp plates D, by their engagement with the rails hold the latter in proper position. 55 The central rail C is held in place between the adjacent arcuate ends of the two clamp plates D.

The clamp plates are detachably secured to the top of the bracket as by screws 6 extending through holes in the clamp plates and screwed into threaded holes in the brackets.

It is evident that when the clamp plates are secured in position the rails are held 65 rigidly in position, but the rails may be released for replacement or repairs by removing the clamp plates.

What I desire to claim is:—

1. In a support for cafeteria rails, the 70 combination of a bracket having lugs thereon and said lugs being provided with an arcuate face against which one side of the rails fit, and a clamp-plate detachably secured to the bracket and having its ends 75 provided with an arcuate surface which fits against the other side of the rails opposite the lugs whereby the rails are held fixedly in position.

2. In a support for supporting parallel 80 circular cafeteria rails, the combination of a bracket having a pair of spaced apart lugs whose adjacent faces are provided with arcuate surfaces which fit respectively against the outer sides of the rails, and clamp-means 85 detachably secured to the bracket intermediate of the lugs and having its ends provided with arcuate surfaces which fit the inner sides of the rails opposite the lugs whereby the rails are fixedly held in position. 90

3. In a support for supporting a plurality of parallel cafeteria rails, the combination of a bracket having a pair of spaced apart lugs whose adjacent faces are provided with arcuate surfaces which fit from without the 95 side of rails, and a pair of clamping-bars detachably secured to the bracket between the lugs, the outer ends of said bars having arcuate portions which fit the rails from within opposite the lugs and whose inner 100 ends are provided with arcuate portions which grip an intermediate rail between them.

Signed at Pittsburgh, Pa., this 5th day of October 1925.

JOHN EDWARD GLOEKLER.
